UNITED STATES PATENT OFFICE.

ALBERT R. PRITCHARD, OF ROCHESTER, NEW YORK.

DESIGN FOR METAL-WARE STOCK.

SPECIFICATION forming part of Design No. 24,316, dated May 14, 1895.

Application filed April 6, 1895. Serial No. 544,760^{1/4}. Term of patent 7 years.

To all whom it may concern:

Be it known that I, ALBERT R. PRITCHARD, a citizen of the United States, and a resident of the city of Rochester, Monroe county, New York, have invented and produced a new and original Design for Metal-Ware Stock, of which the following is a specification, reference being had to the accompanying drawings, in which—

10 Figure 1 is a side elevation of a piece of metal formed according to my design, and Fig. 2 is a top plan view of the same.

The principal feature of my design is the convex portion A provided with the oval beads

15 or ornaments a a which are formed thereon by stamping, if sheet metal is used, or which

are cast thereon, if cast metal is used. The said oval beads or ornaments a a are formed in relief upon the convex surface A of the metal; and around the base of the portion A ²⁰ is a bead a'.

This stock is used in connection with the manufacture principally of vessels of metal, and ordinarily forms part of the top portion ²⁵ of such vessels.

What I claim is—

The design for metal ware stock substantially as shown and described.

ALBERT R. PRITCHARD.
